UNITED STATES PATENT OFFICE

ALPHEUS W. ALTORFER, OF PEORIA, ILLINOIS

WRINGER

Application filed January 4, 1926. Serial No. 79,074.

This invention relates to wringers.

More particularly, the invention has reference to means functioning to facilitate attachment and detachment of a wringer to a wringer head.

The invention includes also means for pivotally relating the wringer to the wringer head to permit the wringer to be swung outwardly while still maintaining its pivotal relation with the head, and thereafter to be separated by simple vertical lift action from such connection.

The invention includes further relative arrangement of the connecting parts between the wringer head and wringer that driving and driven members respectively in the wringer head and wringer may be brought into clutched relation when the parts are assembled in operative relation, or that they may be readily separated by simple swinging action.

The invention is specially directed to a detachable connecting means between the wringer head and wringer that includes an open pivot seat on the one or the other member, the head or the wringer frame, that makes the wringer frame detachment simple and easy, and also serves to effect centering between the driving and driven members respectively of the head and wringer.

The invention comprehends releasable locking means between the wringer and the wringer head.

Referring to the drawings, in which the same numbers refer to the same parts throughout the several views—

Fig. 1 is a front elevation, partially in broken section, disclosing a wringer and wringer head and showing the detail manner of connectedly relating the same in a manner to permit ready separation.

Fig. 2 is a top view, in part, of the same subject matter disclosed in Fig. 1.

Fig. 3 is a composite figure in elevation, showing parts respectively of a wringer head and wringer in separated relation, illustrating relative positions of members at the juncture of separation.

In the drawings, 10 refers generally to a portion of a standard member of form, com-

monly applied to the framework of washing machines; 11 is a wringer head member adapted to be pivoted in the well known manner of such heads in conjunction with a standard; 12 is a vertical drive shaft, supported in 55 the wringer head, and 13 is a driven shaft also supported in the wringer head and having a clutch member 14 thereon. 15 is a wringer shaft having its end portion clutch fashioned as at 16 to engage clutch member 14 on shaft 13.

The wringer head 11 is fashioned at its attachment side for the wringer with a bracket member 17, having a transverse seating slot 18 therein, adapted to receive and 65 seat a pin member connected with the wringer. 19 is a bolt pivoted to the lower portion of the wringer head provided with a wing nut 20 thereon, said bolt and nut forming a part 70 of attachment means to hold the wringer when attached in a stable position.

On the wringer frame, generally referred to as 21, are provided spaced bracket members 22. A pin 23 is supported transversely with respect to said bracket members and secured thereto, said pin serving for attachment connection by seating in bracket seat or slot 18 in the head member. On the lower attachment end of the wringer frame, there are provided relatively spaced lug members 24, the 80 same providing an open seat to facilitate entry of bolt member 19 on the head, whereby, when the wringer frame is attached to the head, permanence of seating may be established by turning wing nut 20 until close-fit relation is established between the engaged parts respectively of the head and wringer frame.

In connection with the utilities of a washing machine, it is desirable at times to remove the wringer that the top of the washing machine may serve for purpose of a table, also, it is desirable to remove the wringer for purposes of shipment. The device presented 90 affords a very convenient and simple means to attain the result of detachability of the wringer from the head, and possesses features of advantage over other detachable means for wringers with which applicant is 100

familiar that render it more serviceable and simple for service.

One form of embodiment of the invention is disclosed herein that from test has demonstrated its utility. However, the invention is broadly directed to a releasable pivotal connection between the wringer head and the wringer that enables it to be swung from a given connecting point between the head and the wringer frame to facilitate separation of the driving connection, and the open connection is provided to facilitate simple bodily lift to accomplish complete disconnection, and the claims are directed to the new structure here presented.

What I claim is:

1. In combination, a wringer head, a driven member therein, a wringer frame, a roller shaft therein, means respectively on the driven member of the head and the roller shaft for effecting detachable driving connection therebetween, means on the wringer head and frame respectively comprising an upwardly open slot on the wringer head and a pivot pin on the frame for effecting detachable pivoted connection therebetween at the upper portion respectively of the wringer head and frame, and interlocking means respectively on the lower portion of said head and frame.
2. In combination, a wringer head, a driven member therein, a wringer frame, a roller shaft therein, means respectively on the driven member of the head and the roller shaft for effecting detachable driving connection therebetween, and means on the wringer head and frame respectively comprising an upwardly open slot on the wringer head and a pivot pin on the frame for effecting detachable pivoted connection therebetween at the upper portion respectively of the wringer head and frame.

In testimony whereof, I have hereunto affixed my signature.

ALPHEUS W. ALTORFER.
